UNITED STATES PATENT OFFICE.

ALBERT E. TODD, OF SEATTLE, WASHINGTON.

FOLDING IRONING BOARD.

Application filed September 8, 1924. Serial No. 736,437.

My invention relates to improvements in folding ironing boards and the object of my invention is to improve and simplify the construction of ironing boards and render 5 the same more substantial in construction, more compact when folded and easier to fold and set up for use.

Another object is to provide a folding ironing board having, toward the forward end, 10 a brace or support slidably connected with the top board at its upper end and arranged to assume a substantially vertical position when the board is set up, the brace being connected at the bottom end with a leg member that extends at an incline from the rear 15 end of the board forwardly and downwardly to the floor, which brace or support is pivotally connected near its upper end with a folding brace or support that is pivotally connected near the lower end of the rear structure, said folding brace and slideable brace 20 contributing to the production of a strong and rigid supporting structure that may be folded and unfolded very quickly and easily 25 and that is very compact when folded.

I accomplish these objects by devices illustrated in the accompanying drawings, wherein—

Figure 1 is a view in side elevation of an ironing board constructed in accordance with 30 my invention showing the same in the open position;

Fig. 2 is a side elevation of the same showing the leg structures partly folded;

Fig. 3 is an end elevation of the board as 35 it may appear when it is set up for use; and

Fig. 4 is a sectional view on line 4—4 of Fig. 1.

Referring to the drawings, throughout 40 which like reference numerals indicate like parts, 5 designates an ironing board having at its rear end on the bottom side a transverse reinforcing strip 35 rigidly secured thereto to prevent warping and having directly in front of the strip and adjacent the 45 respective edges of the board two blocks 6 and 7 through which extends a transverse pivot member 8 whereon are mounted two divergent rear supporting legs 9, whose upper ends are disposed on the outer sides of the 50 respective blocks 6 and 7. The two rear sup-

porting legs 9 are rigidly connected with each other by an upper cross-brace 10, a lower cross-brace 11, two angular brace members 12 and 13 and two spaced upright brace 55 members 14 and 15, whose upper ends are secured to the upper cross-brace 10 and the lower cross-brace 11 respectively, the upper ends of the angular brace members 12 and 13 being secured to the upright members 14 60 and 15. The blocks 6 and 7 rest upon the upper cross-brace 10 when the board is set up for use, two pads 16 of resistant material, as rubber, being mounted between the blocks 6 and 7 and the cross brace 10 so as 65 to be positioned between the cross-brace 10 and blocks 6 and 7.

The numeral 17 is a front leg member composed of two pieces that are secured together at their front or lower end, thence extend 70 rearwardly and upwardly in divergent relation and have their upper ends positioned just inside the respective blocks 6 and 7 and are mounted for swinging movement on the pivot 8.

A cross-bar 18 between the two pieces of the front leg 17 toward the lower or convergent end thereof holds said two members apart 75 and does not interfere with the other members of the leg structure when folded.

An upright brace or support formed of two members 20 and 21 that are spaced a short distance apart at their upper end and rigidly connected by a metal bracket 22, preferably a round rod having its ends bent at 85 right angles and flattened and secured by screws 23 to the members 20 and 21, is provided for supporting the forward end of the board 5. The lower ends of the members 20 and 21 are secured by a transverse pivot 24 90 to the front leg member 17 in such a position as to cause the brace formed by the members 20 and 21 to assume a substantially upright position when the board is set up for use.

The bracket 22 serves as a support on 95 which the board 5 may rest and is slideable on a guide rod 25 that extends lengthwise along the bottom of the board 5 in slightly spaced relation therefrom. The front end 100 of guide rod 25 is made fast to a cross-bar 26 that is secured to the board 5 and that serves the triple function of a mounting for

guide rod 25, a stop or support against which the bracket 22 may rest, and a reinforcing strip that strengthens the ironing board 5 and prevents the same from warping. The rear end of the guide rod 25 may be bent upwardly and flattened substantially as shown and secured to the ironing board.

The guide rod 25 together with the 10 bracket 22 provides the means for automatically positioning the structural parts to their proper positions when folding and unfolding the board and also prevents the board 5 from being lifted away from the 15 brace formed by the members 20 and 21 when it is desired to move the whole structure to a new position.

A folding brace member formed of two pieces 27 and 28 connected with each other 20 by a hinge 29 is secured at one end by a pivot 30 to the upright supporting members 20 and 21 near the upper end and at the other end by a pivot 31 to the upright brace bars 14 and 15 on the rear leg structure 25 and is arranged, when in the open or set up position to rest on a pin 32 that extends crosswise of the two convergent front leg members 17 between which it passes, the center of the hinge 29 being slightly below 30 a straight line that passes through the pivots 30 and 31 when extended so that said folding brace member will always tend to remain in the open position shown in Fig. 1, except when it is forcibly displaced from 35 that position in folding the supporting structure upwardly against the board.

When the ironing board is in an open position the folding brace spreads the supporting legs 9 causing the cross-brace 10 to bear 40 against the pads 16 and blocks 6 and 7 and also spreads the upper end of the members 20 and 21 having the bracket 22 thereon urging the bracket 22 against the cross-bar 26 whereby the whole structure becomes 45 rigid. The pads 16 being provided so that the cross-brace 10 will not be permanently depressed and will at all times cause a tight contact when the board is in an open position.

50 It will be obvious from the foregoing that the pressure exerted against the blocks 6 and 7 will have a tendency to cause the top of the bracket 22 to bear against the top of the board 5 and hold it there in fixed relation thereto.

In folding the board a pressure is exerted below the folding brace members 27 and 28 to cause the center of the hinge 29 to pass upwardly beyond the line of centers through 60 pivots 30 and 31 after which the brace members 27 and 28 are free to fold together flatly one on the other, drawing the upper end of the members 20 and 21 rearwardly, bracket 22 sliding on guide rod 25 and making it 65 possible to fold the front and rear leg struc-

tures forwardly and upwardly against the board 5.

In the completely folded position the members 20, 21, 27 and 28 lie between the front leg members 17 and rear leg members 70 9 fold outside of front leg members 17 thus making a very compact structure.

To open the ironing board for use the top is lifted and the folding brace 27 and 28 is pressed downwardly thereby causing the 75 several parts of the structure to assume their proper positions.

The foregoing description and accompanying drawings clearly disclose a preferred embodiment of my invention but it 80 will be understood that changes in the details of construction may be resorted to without departing from the spirit thereof.

What I claim is:

1. In a folding ironing table structure, a 85 board, a rear leg structure pivoted thereon, a front leg pivoted to the rear of said board and extending forwardly and downwardly therefrom, a support pivoted to the front leg and arranged to stand substantially vertical for supporting the forward end of the board, means slidably connecting the upper end of the support with the board, and a collapsible brace member one end of which is pivoted to the upper end 95 of said support and the other end of which is pivoted to the lower portion of said rear leg of the structure.

2. In a folding ironing table structure, a 100 board, a rear leg structure pivotally connected with the rear end of the board, a front leg structure pivoted to the rear end of the board and arranged to extend forwardly and downwardly, a support pivoted to the front leg structure and arranged to 105 stand substantially vertical for supporting said board at a point forward of the center means for slidably connecting the upper end of said support with said board, and a folding brace having a hinge connection substantially midway between its two ends, the respective ends of said brace being pivoted to the upper end portion of said support and the lower end portion of said rear leg structure.

3. In a folding ironing table structure, a 115 board, a rear leg structure pivotally connected with the rear end portion of the board, a front leg structure pivoted to the rear end portion of said board, and arranged to extend forwardly and downwardly therefrom, a support pivoted to the front leg structure and arranged to stand substantially vertical for supporting said board at a point forward of the center, a guide rod 120 secured to the bottom of said board and extending lengthwise thereof, a bracket secured to the upper end of said support and slidably along said guide rod and affording a relatively wide bearing on which the 130

board may rest, a folding brace formed of two parts of substantially equal length articulately connected by a hinge and having its ends pivoted respectively to the upper end portion of said brace and the lower end portion of said rear leg structure, and stop means rigid with said front leg struc-

ture against which said folding brace may rest when extended.

In witness whereof, I hereunto subscribe my name this 30th day of August A. D., 1924.

ALBERT E. TODD.
